UNITED STATES PATENT OFFICE

117,663

DESIGN FOR AN UMBRELLA

Edward J. Doty, Baltimore, Md., assignor to Polan, Katz & Company, Baltimore, Md., a co-partnership composed of Jesse N. Polan, Charles Katz, and William L. Fox

Application November 3, 1938, Serial No. 80,854

Term of patent 3½ years

To all whom it may concern:

Be it known that I, Edward J. Doty, a citizen of the United States, residing at Baltimore city, and State of Maryland, have invented a certain new, original, and ornamental Design for Umbrellas, of which the following is a specification, reference being had to the accompanying drawing, forming part thereof.

The characteristic features of my design reside in an umbrella of the character shown in which the design of the goods and panels alternate in staggered relation, as best shown in the drawing.

I claim:

The ornamental design for an umbrella, as shown and described.

EDWARD J. DOTY.
